UNITED STATES PATENT OFFICE.

BIRD M. SYPHER, OF TOLEDO, OHIO.

ELECTROMAGNETIC SEPARATOR FOR GRAIN-CHUTES.

933,930.

Specification of Letters Patent. Patented Sept. 14, 1909.

Application filed June 22, 1908. Serial No. 439,696.

To all whom it may concern:

Be it known that I, BIRD M. SYPHER, a citizen of the United States, residing at Toledo, in the county of Lucas and State of Ohio, have invented a new and useful Improvement in Electromagnetic Separators for Grain-Chutes, of which the following is a specification.

My invention relates to an electromagnetic separator for grain chutes and has for its object to provide an efficient separator of the kind, having strong magnetic attraction to thoroughly separate from grain passing through a chute any magnetic particles or substances that are mingled with the grain.

A further object is to provide a separator of the kind, with means to automatically remove from the electromagnet and from the chute of the separator the substances that are attracted to the magnet.

I accomplish these objects by the construction and combination of parts as hereinafter described and illustrated in the drawings, in which—

25 Figure 1 is a longitudinal, vertical section of a broken away portion of a grain chute, having attached thereto a separator constructed in accordance with my invention and shown in side elevation partly in sections. 30 Fig. 2 is a horizontal longitudinal section of the same, showing the top plan view of my separator, and Fig. 3 is a perspective view of the electromagnet of my separator detached from the chute, and partly broken 35 away at one side and end to show the inner core and windings.

In the drawings 1 designates a grain chute having attached thereto a separator constructed in accordance with my invention 40 and comprising an electromagnet 2, connected by the conductors 3 and 4 with a dynamo, (not shown), and a wiper 5 for the magnet 2, a wheel 6 adapted to reciprocate the wiper, a worm wheel 7 adapted to revolve the wheel 6, and a pulley 8, mounted on a shaft 9, having a worm 10 engaging the worm wheel 7, and adapted to revolve the worm wheel. The electromagnet 2 comprises the rectangular soft iron plate core 11 projecting centrally 45 and longitudinally from the base 12 of a rectangular channel shaped soft iron body 13, having the sides 14 projecting from the base 12 parallel with the core 11, the insulated winding 15 around the core 11, the top plate 50 winding 15 of compressed fiber 16, around the core flush with the outer free end of the core and the

outer edges of the sides 14 of body 13, and the fiber plates 17, flush with the ends of the base 12 and the sides 13. Preferably the space between the side 14, the base 12, the 60 end plates 17, and the top plate 16, and the winding 15 of the core is filled with paraffin. The sides 14 are provided with the insulating fiber plates 18, to which are secured the binding posts 19 which are connected to the 65 winding 15, and by the conductors 3 and 4 to the dynamo, (not shown). The electromagnet thus constructed is fitted into a suitable opening in the bottom of the chute 1 with the top face flush with the inner face 70 of the bottom.

The wiper 5 is mounted on a stud pin 20, projecting from the bottom of the chute 1, with one arm 21 projecting over the top side of the wheel 6. The arm 21 is provided with 75 a slot 22 through which projects a crank pin 23 of the wheel 6. The opposite arm 24 of the wiper extends downward of the chute 1, and is provided at its outer end with a wiper plate 25 of non-magnetic material, 80 which extends over and is adapted to engage the top face of the electromagnet.

The wheel 6 is fixedly mounted on the axle 26 which extends downward through the bottom of the chute 1, and through a bearing 27 secured to the outer face of the bottom, and upon a projecting end portion of the axle abutting the bearing is fixedly mounted the worm wheel 7. To the bottom of the chute 1 are also secured the bracket 85 bearings 28 in which is journaled the shaft 9 of the worm 10, with the worm intermeshing with the worm wheel 7.

To the sides of the chute 1, opposite the top edges of the ends of the electromagnet 2, 95 are provided openings which are closed by the doors 29 hinged at the lower ends of the openings, and the doors 29 are normally held closed by the springs 30, each secured at one end to a side of the chute, and extending 100 along a door. Above the doors the sides of the chute 1 are provided on their inner faces with the deflecting plates 31, adapted to deflect the grain passing through the chute next the sides while passing the doors. 105

Thus constructed, connected and attached as described to a grain chute, the operation of my invention is as follows:—The current transmitted by the conductors 3 and 4 from the dynamo through the winding 15, converts the core 11 and the sides 14 into magnets which attract any magnetic particles or 110

substances mingled with the grain, and carried thereby through and along the chute, thereby separating them from the grain. If these particles were left to accumulate on the magnet, they would in time produce an obstruction in the path of the grain, and the outer particles of the accumulation being more weakly held by the magnet than those contacting directly therewith, would be liable to be detached therefrom by the grain in passing over the magnet. To obviate this I have provided the wiper 5, the lower and longer arm 24 of which is slowly reciprocated from side to side of the chute by the action of the crank pin of the wheel 6 engaging the shorter arm, thereby moving the wiper plate which is in engagement with the upper face of the magnet, slowly back and forth over it, thereby scraping from the face any magnetic particles adhering thereto toward the doors 29, which, at the ends of the stroke of the wiper plate, in either direction, are engaged by the plate and opened, and the magnetic particles accumulated by the magnet are pushed through the door openings over the ends of the magnet, and outside the chute, the springs 30 operating to close the doors as the wiper plate recedes therefrom.

By the use of an electromagnet constructed, connected and attached to a chute as described, I provide a degree of magnetism that is not possible to attain with the permanent magnets usually employed for the purpose, and thereby produce a more thorough separation of magnetic substances from the grain, and by combining with the electromagnet the means described for continuously removing the magnetic accumulations from the magnet and the chute. I have provided for the full effective action of the magnet at all times, and against detachment of the outer portions of excessive accumulations on the magnet, that through the weakness of the magnetic attraction on such outer portions are liable to be detached therefrom by the grain passing over it and again mingled therewith.

What I claim to be new is—

1. The combination with a grain chute having a bottom, and sides provided with opposite openings, of outwardly opening and automatically closing doors for the side openings, an electromagnet, comprising a channel shaped rectangular soft iron body, a core plate projecting from the base of the body, centrally and longitudinally between

and parallel with the sides of the body, a winding around the core plate between the sides of the body, insulating material around the winding and filling the space between the sides of the body flush with the outer edges of the sides, and conductors adapted to connect the winding in an electric circuit, the magnet being transverse the bottom of the chute between the doors with the ends of the poles and core flush with and transverse the inner face of the bottom, a wiper plate for the magnet, and means to reciprocate the wiper plate over the magnet from door to door, and to alternately engage and open each door with the wiper plate.

2. In an electromagnetic separator for grain, the combination of a chute having a bottom, and sides provided with opposite openings, and with downwardly converging deflector plates contacting the channel of the chute above the openings, an electromagnet having poles flush with and transverse the inner face of the bottom between the side openings, outwardly opening and automatically closing doors for the openings, means to remove magnetic accumulations from the poles of the magnet comprising a non-magnetic wiper plate, adapted to be reciprocated to and from engagement with the doors respectively, over and in engagement with the poles of the magnet, and means to reciprocate the wiper plate.

3. The combination with a chute, of a magnet transverse the bottom of the chute flush with the inner face of the bottom, a wiper lever pivotally mounted in the chute parallel with the bottom and having a long arm provided with a non-magnetic wiper plate extending over and engaging the magnet, and a slotted short arm, a disk wheel in the chute parallel with the bottom, and having a fixed axle extended through the bottom and journaled beneath the short arm of the lever and a pin eccentric to the axle extending through the slot of the short arm, a worm wheel fixed on the axle of the disk wheel outside the chute, a worm intermeshing with the worm wheel and means to revolve the worm, substantially as set forth.

In witness whereof I have hereunto signed my name in the presence of two subscribing witnesses, this 15th day of June, 1908.

BIRD M. SYPHER.
